Asahel Cooley.

UNITED STATES PATENT OFFICE.

ASAHEL COOLEY, OF SPRINGFIELD, ILLINOIS.

PUMP.

Specification of Letters Patent No. 22,165, dated November 30, 1858.

To all whom it may concern:

Be it known that I, ASAHEL COOLEY, of Springfield, in the county of Sangamon and State of Illinois, have invented a new and 5 useful Improvement in Double-Acting Suction and Force Pumps; and I do hereby declare that the following is a full, clear, and exact description of the construction and operation of the same, reference being had 10 to the annexed drawings, making a part of this specification, in which—

Figure 1 is an isometrical view; Fig. 2 a longitudinal elevation; Fig. 3 an isometrical view, of the piston with its valves and connections; and, Fig. 4 a sectional view of the 15 pitmen $K K'$, and the manner of their attachment to lever H , and ring I . (Fig. 1.)

A is the suction chamber; $B B'$ the cylinder; $C C'$ the air chamber; $D D'$ the discharge pipe; $E E'$ the piston; $F F'$ its upper valve; $G G'$ its lower valve; $H H'$ working lever; $I I'$ ring around the discharge pipe; $K K'$ pitmen for connecting the lever to the ring; and, L a transverse 25 section of the pitmen.

To enable others skilled in the art to make and use my invention, I will proceed to describe its construction and operation.

Construction.—The suction chamber, 30 consists of a hemispherical chamber, with pipes extending downward from ports $a a$, and a port below for receiving the liquid from the supply pipe. The form of the cylinder is readily understood by the drawings.

The air chamber, is a spherical chamber 35 with a pipe extending downward through the center, to receive the liquid from the bottom.

The piston is a circular disk, with a circular opening through the center; and has two valves F and G which alternately close the openings to form vacuums in the cylinder above and below the piston. Valve F is hemispheroid, funnel shape, or of any 40 convenient form, and has a hole through the top, for discharging the liquid into the discharge pipe, to which it is attached. This valve is attached to bolt s , by wings $c c c$ or their equivalent. F , $c c c$, and s , is one piece, the bolt and wings of which 45 pass through the opening of the piston and the bolt extends below the wings, and is attached to valve G below the piston. The length of the wings below the lower rim of 50 valve F , being greater than the thickness of

the piston at the opening, allows space for working the valves.

The packing of the piston, consists of a strip of leather or other suitable material, placed around the circumference of the piston, and secured with a wire, which binds the center of the strip into a groove. 60

A reciprocating motion is communicated to the piston, by pitmen $K K'$ which attach the working lever, to ring I , which is secured to the discharge pipe with a set screw. 65

$e e$ (Fig. 4) are cross sections of the extremities $i i$ of the pitmen. They are circular in shape, having two points extending from opposite sides, on lines $i i$, $i i$, which hold the pitmen in their proper position. The holes for the reception of the pitmen, 70 are of the same form as the cross sections $e e$, having two slots on opposite sides on lines $x x$, for receiving the points of the pitmen. 75

When the ends of the pitmen are so placed that lines $i i$, coincide with lines $x x$, they may be passed through the holes, to the opposite sides, where recesses are formed, the diameter of which is equal to the extremity 80 of the points, on line $i i$, and of sufficient depth to allow the points to turn in the recesses. When the pitmen are placed in the holes, and turned so that lines $i i$, are perpendicular to lines $x x$, they are in their 85 working position, and can vibrate freely when the pump is worked and the points working in the recesses hold them in their places.

Materials.—The materials of the pump 90 are mostly iron. The handle of the lever is wood, valves $F G$, and their connections, valves $b d$, stuffing box g and a section of pipe working through the stuffing box and connecting with valve F are generally brass. 95

Operation.—As the lever rises valve G is drawn against the piston forcing it upward, valve b is raised, and the cylinder is filled below the piston. When the stroke of the piston is reversed, valve b closes the corresponding port; valve F presses the piston downward; valve E drops below the piston; and the liquid is forced through the intervening space; between wings $c c c$, through valve F , air chamber, and discharge pipe. 100 As the piston descends, and the liquid discharges, as above described, the space between valve F and the piston being closed, the valve d is raised, and the liquid flows through passage f and fills the cylinder 105 110

above the piston. When the stroke is again reversed, the cylinder is again filled below the piston; valve *d* drops; valve *F* is raised above the piston; and the liquid is forced 5 through the intervening space; valve *F*; and discharged. When the piston is raised to its highest point, valve *F* fills the recess above, and its lower rim being even with the top of the cylinder, the air (should there be any in 10 the cylinder above the piston) escapes into the air chamber. Should there be any air below the piston, it escapes before the water is discharged from the cylinder. When the pump is filled, and remaining at rest, the 15 upper surface of the liquid in the suction chamber, is at the lower ends of the pipes extending from ports *a a*; but when it is working, and either of valves *b*, *d*, drops, the liquid continues flowing into the chamber, until the other valve rises, when it 20 flows into the cylinder, faster than it flows in the chamber, until its surface is again even with the ends of the pipes. A vibration of the liquid in the chamber continues, 25 as ports *a a* are alternately opened, and closed, while an unbroken current flows from the supply pipe, avoiding a reaction, or flowing back, of the liquid in the supply pipe by the closing of the ports.

30 *Advantages.*—The advantages of the pump are, 1st, its capacity for discharging the air from the cylinder; 2nd, an unbroken current from the supply pipe; 3rd, a direct water course, the water that discharges from 35 above the piston, having but a slight change of direction, while that from below the pis-

ton, passes in a straight line from the bottom to the top of the well, and, 4th, it dispenses with a piston rod for working it in deep wells, the pipe working in its stead, being lighter than a piston rod of the strength 40 required.

By avoiding an accumulation of air in the cylinder, the pump discharges more with a given rate of speed; it draws by atmospheric pressure with more promptness; and this, with an unchecked current from the supply pipe, enables it to draw from a much greater distance; and with a continuous current from the supply pipe, and direct passage through the cylinder, it is worked with 45 much less power.

Having thus described the construction and operation of my improvement, and enough of the remainder of the pump, to 50 show the nature and utility of said improvement, I disclaim suction chamber *A*; cylinder *B*; and air chamber *C*, as they do not differ materially from others in use.

I claim—

1. The parts *E*, *G*, *F*, *s*, and *c*, *c*, *c*, composing the piston and its valves when combined with the hollow piston rod *D*, substantially as above described.

2. I claim the parts *H*, *K*, and *I*, constructed as above described when combined with the hollow piston rod *D*, for the purposes and in the manner above described.

ASAHEL COOLEY.
